UNITED STATES PATENT OFFICE.

FRED BIFFAR, OF CHICAGO, ILLINOIS.

DESIGN FOR A REVOLVER OR PISTOL HANDLE.

47,984.

Specification for Design.

Patented Oct. 19, 1915.

Application filed December 7, 1914. Serial No. 875,982. Term of patent 14 years.

To all whom it may concern:

Be it known that I, FRED BIFFAR, a citizen of the United States, residing at Chicago, in the county of Cook and State of Illinois, have invented a new, original, and ornamental Design for a Revolver or Pistol Handle, of which the following is a specification, reference being had to accompanying drawing, forming a part thereof.

Figure 1, is a side elevation of a revolver or pistol handle embodying my invention and Fig. 2, is a sectional view taken on line 2—2 of Fig. 1.

Similar reference characters refer to similar parts throughout both views.

The main body of the handle 3 is prefer-

ably made of dark or black material and the inlaid portions 4, 5, 6, 7, 8 and 9 are preferably made of a light colored material to make a contrast between the handle and the inlays.

I claim:—

The ornamental design for a revolver or pistol handle, as shown and described.

In testimony whereof I have signed my name to this specification in presence of two subscribing witnesses this 24th day of November, 1914, at Chicago, Illinois.

FRED BIFFAR.

Witnesses:

MILTON N. MILLER,
RICHD. J. JACKER.
